UNITED STATES PATENT OFFICE.

WILLIAM G. LEAZAR, OF KERRVILLE, TEXAS.

RIVETING APPARATUS.

Application filed July 29, 1924. Serial No. 723,931.

To all whom it may concern:

Be it known that WILLIAM G. LEAZAR, a citizen of the United States of America, residing at Kerrville, in the county of Kerr and State of Texas, has invented new and useful Improvements in Riveting Apparatus, of which the following is a specification.

It is a purpose of the present invention to provide, in a riveting apparatus, a construction particularly adapted for riveting arms upon crank cases, especially those of the Ford type, and in carrying this process into effect the invention includes a riveting block with means for fastening the same on a bench or a horse, whereby the crank case may be placed so that, when the rivets which are to secure the arms to the crank case engage with the block, improved clamps are used to fasten the crank case in position, subsequently to which a mechanic may proceed to heat the rivets with a torch and set them with a riveting set or hammer.

It is to be understood that the particulars herein given are in no way limitative and that, while still keeping within the scope of the invention, any desired modifications of detail and desired proportions may be made in the apparatus according to the circumstances.

The invention comprises further features and combinations of parts to be hereinafter set forth, shown in the drawings and claimed.

In the drawings:

Figure 1 is a view of the improved riveting apparatus constructed in accordance with the invention and illustrating a crank case in position thereon for riveting the arms in position.

Figure 2 is a central vertical sectional view of the invention, illustrating how the rivets engage with the riveting block and how the clamps are applied.

Figure 3 is a detail view of the riveting block.

Figure 4 is a detail view of a portion of the riveting block and the support 16.

Figure 5 is a detail view of a portion of the support 16 and the holder 20.

Referring to the drawings, 1 designates the riveting block which is provided with a pair of projections 2 and 3 which are designed to enter openings 4 and 5 of corresponding size to the diameter of the projections, said openings being formed in a bench, horse or other similar support. The

latter projection 3 is longer than the projection 2 and is threaded at its terminal for the reception of a nut to retain the riveting block in position. The projection 2 is provided primarily for preventing lateral movement of the block.

The upper face of the riveting block near one end has a transverse groove 6 and adjacent its other end has an elongated depression or seat 7, there being a transverse opening 8 to receive a pin 9 which passes through an opening 10 in one end of a gooseneck clamp 11. The end of the clamp which engages in the seat or depression 7 is elongated in cross sectional area corresponding to and fitting within the seat, the fit being secure enough to prevent lateral movement of the clamp and also relieve any great amount of strain upon the pin.

The terminal 12 of the gooseneck clamp 11 extends laterally and threaded therethrough is a clamping screw 13. The screw 13 has a winged head 14 and a swiveled foot 15 which engages with the crank case and retains the arm to be riveted in position upon the riveting block.

However, before placing the crank case and arm in position, a support 16 is employed. This support 16 comprises a U-shaped end 17 which straddles the riveting block, the transverse portion 18 of which engages in the groove 6 so that the arm 19 of the support may project in such wise as to assist in supporting one end of the crank case.

A holder 20 is provided for suspension on the arm of the support 19 to withstand the weight of the front end of the Ford crank case. This holder is adjustable or slides along the arm of the support 19 until the three rivets in the crank case arm are level on the riveting block, then the screw 13 may be tightened on the arm, hence permitting the mechanic to proceed to heat the rivets through the medium of an acetylene torch and rivet set or hammer.

In the operation of heading the rivets for securing arms to a Ford crank case, the riveting block is supported, as previously stated, on a bench or horse, after which the holder 20 is engaged or connected with the right or left arm of the crank case. The rivets for securing the arms to the crank case are then secured in position through the arms and the wall of the crank case, and then the crank case is placed in position

on the riveting block. The holder is adjusted along the arm 19 to the proper position until the rivets all touch or engage with the riveting block. The clamp 11 is then disposed in position, the base end of which engages in the depression or seat 7 and fastened with the transverse pin. The clamping screw is then tightened so that its foot may tighten against the crank case and arm, fastening them to the riveting block. Subsequent to this, the mechanic is at liberty to proceed with the usual acetylene torch for the purpose of heating the rivets, after which they may be headed with a conventional form of rivet set or hammer. A single operator or mechanic may easily operate the apparatus without assistance.

The invention having been set forth, what is claimed is:

- 20 1. A riveting apparatus for riveting arms on crank cases, the same comprising a riveting block provided with means for holding it on a bench or other support, a supporting member carried by the riveting block and having a laterally projecting arm, a holder suspended from said arm and adapted to support a crank case at a point remote from the riveting block, and a clamp operatively supported on the riveting block for bearing engagement upon a crank case arm and holding it in contact with the crank case and the latter in contact with the riveting block.
- 25 2. A riveting apparatus for riveting arms on crank cases, the same comprising a riveting block provided with means for holding it on a bench or other support, a supporting member carried by the riveting block and having a laterally projecting arm, a holder suspended from said arm and adapted to support a crank case at a point remote from the riveting block, and a clamp operatively supported on the riveting block for bearing engagement upon a crank case arm and holding it in contact with the crank case and the latter in contact with the riveting block.
- 30 3. A riveting apparatus for riveting arms on crank cases, the same comprising a riveting block provided with means for holding it on a bench or other support, a supporting member carried by the riveting block and having a laterally projecting arm, a holder suspended from said arm and adapted to support a crank case at a point remote from the riveting block, and a clamp operatively supported on the riveting block for bearing engagement upon a crank case arm and holding it in contact with the crank case and the latter in contact with the riveting block.
- 35 4. A riveting apparatus for riveting arms on crank cases, the same comprising a riveting block provided with means for holding it on a bench or other support, a supporting member carried by the riveting block and having a laterally projecting arm, a holder suspended from said arm and adapted to support a crank case at a point remote from the riveting block, and a clamp operatively supported on the riveting block for bearing engagement upon a crank case arm and holding it in contact with the crank case and the latter in contact with the riveting block.
- 40 5. A riveting apparatus for riveting arms on crank cases, the same comprising a riveting block provided with means for holding it on a bench or other support, a supporting member carried by the riveting block and having a laterally projecting arm, a holder suspended from said arm and adapted to support a crank case at a point remote from the riveting block, and a clamp operatively supported on the riveting block for bearing engagement upon a crank case arm and holding it in contact with the crank case and the latter in contact with the riveting block.
- 45 6. A riveting apparatus for riveting arms on crank cases, the same comprising a riveting block provided with means for holding it on a bench or other support, a supporting member carried by the riveting block and having a laterally projecting arm, a holder suspended from said arm and adapted to support a crank case at a point remote from the riveting block, and a clamp operatively supported on the riveting block for bearing engagement upon a crank case arm and holding it in contact with the crank case and the latter in contact with the riveting block.

said clamp comprising a goose-neck arm detachably engaged in a seat on the riveting block.

3. A riveting apparatus for riveting arms on crank cases, the same comprising a riveting block provided with means for holding it on a bench or other support, a supporting member carried by the riveting block and having a laterally projecting arm, a holder suspended from said arm and adapted to support a crank case at a point remote from the riveting block, and a clamp operatively supported on the riveting block for bearing engagement upon a crank case arm and holding it in contact with the crank case and the latter in contact with the riveting block, said support comprising a bar having a U-shaped extremity disposed at right angles to the projecting arm, said U-shaped extremity straddling and engaging a recess in the riveting block.

4. A riveting apparatus for riveting arms on crank cases, the same comprising a riveting block provided with means for holding it on a bench or other support, a supporting member carried by the riveting block and having a laterally projecting arm, a holder suspended from said arm and adapted to support a crank case at a point remote from the riveting block, and a clamp operatively supported on the riveting block for bearing engagement upon a crank case arm and holding it in contact with the crank case and the latter in contact with the riveting block, said support comprising a bar having a U-shaped extremity disposed at right angles to the projecting arm, said U-shaped extremity straddling and engaging a recess in the riveting block, and the holder being suspended from the arm and movable longitudinally therewith.

In testimony whereof he affixes his signature.

WILLIAM G. LEAZAR.
